ULTRAVIOLET RADIATION APPARATUS

Jeanne Goude Axelos, Paris, and André Claude, Nanterre, France, assignors to Société Anonyme pour les Applications de l'Électricité & des Gaz Rares Etablissements Claude-Paz & Silva, a corporation of France

Application June 20, 1932, Serial No. 618,401
In France December 26, 1931

13 Claims. (Cl. 250—35)

The present invention relates to the construction of lamps for utilizing the ultra-violet rays emitted by gases or vapours or a mixture of gases and vapours excited by high frequency electric currents.

The art of utilizing these rays necessitates a particular condition. It is necessary to bring the source of the radiations as close as possible to the part to be irradiated. It is, in fact, known that ultra-violet radiations, particularly those of short wave-length, are very much absorbed by the air. It is necessary, therefore, to avoid the interposition of air between the source and the region to be irradiated, the efficiency depending not so much upon the law of illumination, which is inversely proportional to the square of the distance, as upon the absorption of the radiations by the interposed layer of air.

In medicine, for example, for certain local applications necessitating the use of short wave-lengths, it is expedient to hold the lamp against the part to be irradiated. Since the existing lamps become very hot, the lamp has to be surrounded by a circulation of cold water, which absorbs the radiations, diminishes the efficiency and complicates the apparatus.

An object of this invention is to avoid the disadvantages of the prior art by providing a lamp containing a gaseous and/or vapor filling excited by a high frequency electric field and which has at least one of its walls situated outside of the effect of the high frequency field so that it will remain without cooling at a temperature low enough to permit contact between said wall and parts of a human body.

To amplify the following description, reference will be made to the accompanying drawing in which:

Figure 1 is a diagrammatic view partly in section of one form of the present invention, and

Fig. 2 is a similar view of a modified form of the present invention.

In the lamp according to the present invention, the high-frequency excitation system, which may be outside or inside the enclosure containing the gas or gases or the mixture of gases and vapours, is placed at a sufficient distance from the wall serving for irradiation for the said wall to be situated outside the electro-magnetic field. This wall is thus removed from the action of the high-frequency field which, as is known, produces considerable heating in dielectrics. At the same time, the wall is less exposed to the transmission of heat by conduction from other parts of the lamp.

For this double reason, the radiating wall remains at a sufficiently low temperature to permit it to be applied directly to the part to be treated, without the need for any cooling device.

According to the applications for which the lamp is intended, the wall used for irradiation may be made of any substance of a nature and thickness so chosen as to allow only a certain zone of the useful visible or ultra-violet spectrum to pass for the desired application. Moreover, this wall may be given desirable shape so as to fit closely the shape of the region where the application is to be made. It is thus possible to introduce into cavities or to apply directly to the tissues the wall itself of the lamp, the shape of which has been made appropriate.

As shown in Figure 1 of the accompanying drawing, a tube T of the glass known under the registered trade-mark "Pyrex" about 14 cm. long and 3 cm. in diameter is closed at one end. At this end, on half the tube, is wound externally with adjacent turns a copper wire C having for example a diameter of 2 mm. and a thickness of 0.5 mm. of asbestos insulation. To the other end of the tube is cemented a quartz plate P which is transparent for the visible and ultra-violet spectrum. The lamp is filled with a suitable atmosphere, for example, a mixture of rare gases and mercury vapour. The two end wires A and B of the solenoid S are connected to the terminals of a high-frequency apparatus, for example, a spark-gap diathermy apparatus. A handle D is provided for manipulating the apparatus.

In the form of invention shown in Fig. 2, the solenoid 5 employed for excitation is situated inside the lamp itself. The conductor wire is insulated by any suitable substance, for example by enamel so as to avoid the production of any discharge between the turns. A solenoid of insulating tube, for example of the "Pyrex" glass above referred to, in which is placed the conductor wire, may likewise be disposed inside the lamp. Mercury or certain alloys which are liquid at the working temperature of the lamp may be introduced instead of a conductor wire. In this case, any known device may be provided with a view to preventing the bursting of the glass tube as a result of the expansion of the mercury or the alloy during the working of the lamp.

In these examples of lamps, the principal wall made of "Pyrex" glass which absorbs the ultra-violet rays of mean and short wave-length protects the operator during the entire duration of application and renders unnecessary the use of spectacles of special glass.

With this lamp, local irradiations, for example on the human skin, may be carried out by applying the quartz plate directly against the skin, without any noticeable heating taking place, even 5 at the end of half an hour's working. The quartz plate may be replaced, for example, by pieces of quartz of any desirable shape, as shown diagrammatically at E in dotted lines, and more particularly by a quartz lens for concentrating the radiations.

Several walls may likewise be provided on one and the same lamp with a view to different applications. In the case of Figure 1, for example, the quartz plate may be retained at one end and 15 a quartz lens may be provided at the other end, the manipulating handle being differently disposed.

It will sometimes be advantageous to provide, 20 within the lamp or directly on the outside thereof, reflectors of high reflecting power, for visible rays and ultra-violet rays, for example of known alloys of magnesium and aluminum. Such a reflector is shown at M, in Figure 2, but it may be constructed in any convenient manner, for example by a suitable deposition on the wall of the lamp.

It will be seen that the present invention is 25 directed to apparatus of great simplicity of construction and use, being distinguished clearly from the ultra-violet ray lamps at present known.

Having now particularly described and ascertained the nature of our said invention and in what manner the same is to be performed, we 30 declare that what we claim is:

1. A device for the therapeutic application of ultra-violet radiations emitted by gases excited by high frequency currents, comprising a sealed receptacle containing the gases, and an induction coil situated on the exterior of the sealed receptacle and adapted to be connected to a source of high frequency current for inductively exciting the gaseous content of the receptacle, the receptacle having at least one of its walls 35 formed of material transparent to ultra-violet rays and employed for irradiation, and said wall being separated from the portion of the receptacle about which the coil is positioned a distance sufficiently great to be out of the action of the induced field and to permit the wall, without cooling, to be at a temperature sufficiently low to be applied to the part to be irradiated.

2. A device for the therapeutic application of ultra-violet radiations emitted by gases excited by high frequency currents, comprising a sealed receptacle containing the gases, and an induction coil positioned within a portion of the receptacle and adapted to be connected to a source of high frequency current for inductively exciting the gaseous content of the receptacle, the receptacle having a wall formed of material transparent to ultra-violet rays and employed for irradiation, and said wall being separated from the portion of the receptacle in which the coil is positioned a distance sufficiently great to be out of the action of the induced field and to permit the wall, without cooling, to be at a temperature sufficiently low to be applied to the part to be irradiated.

3. A device for the therapeutic application of ultra-violet radiations emitted by gases excited by high frequency currents, comprising a receptacle for the gases, a coil for inducing current in 75 the gases, and reflectors of high reflecting power

for visible and ultra-violet rays provided in the receptacle.

4. A device for the therapeutic application of ultra-violet radiations emitted by gases excited by high frequency currents, comprising a receptacle for the gases, a coil for inducing current in the gases, and reflectors of high reflecting power for visible and ultra-violet rays provided directly on the outside of the lamp.

5. A device for the therapeutic application of ultra-violet radiations emitted by gases excited by high frequency currents, comprising a sealed receptacle containing the gases, an induction coil associated with a portion of the receptacle and adapted to be connected to a source of high frequency current for inductively exciting the gaseous content of the receptacle, the receptacle having a wall formed of material transparent to ultra-violet rays and employed for irradiation, and said wall being separated from the portion 20 of the receptacle with which the coil is associated a distance sufficiently great to be out of the action of the induced field and to permit the wall, without cooling, to be at a temperature sufficiently low to be applied to the part to be irradiated, and a reflector of high reflecting power for visible and ultra-violet radiations provided in the receptacle and adapted to direct the radiations on said wall.

6. A device for the therapeutic application of ultra-violet radiations emitted by gases excited by high frequency currents, comprising a sealed receptacle containing the gases, an induction coil associated with a portion of the receptacle and adapted to be connected to a source of high frequency current for inductively exciting the gaseous content of the receptacle, the receptacle having a wall formed of material transparent to ultra-violet rays and employed for irradiation, and said wall being separated from the portion of the receptacle with which the coil is associated a distance sufficiently great to be out of the action of the induced field and to permit the wall, without cooling, to be at a temperature sufficiently low to be applied to the part to be irradiated, and a reflector of high reflecting power for visible and ultra-violet radiations provided directly on the outside of the receptacle for directing the radiation to said wall.

7. A device for the application of ultra-violet radiations emitted by gases inductively excited by high frequency currents, comprising a sealed receptacle containing the gases, and an induction coil adapted to be connected to a source of high frequency current for inductively exciting the gaseous content of the receptacle, the receptacle having at least one of its walls formed of material transparent to ultra-violet rays and employed for irradiation, said wall being separated from the portion of the receptacle with which the coil is associated by a distance sufficiently great to be removed from the action of the induced field and to permit the wall, without cooling, to be applied directly to the part to be irradiated.

8. A device according to claim 1, in which all walls of the receptacle are formed of material transparent to ultra-violet rays.

9. A device according to claim 7, in which all walls of the receptacle are formed of material transparent to ultra-violet rays.

10. An apparatus for the application of ultra-violet radiations directly to portions of the human body, comprising an envelope containing a gaseous filling and having at least one wall formed of material transparent to ultra-violet radiations, and means for electrically exciting the gaseous

- filling to produce ultra-violet radiations, said ultra-violet radiation transparent wall and the exciting means being sufficiently spaced apart so that the wall is outside of the action of the exciting field produced to avoid the heating effect of said field and to permit direct contact between said wall and the portion of the body to be irradiated without extraneous cooling.
11. A device according to claim 1, in which the walls of the receptacle are of a substance different from the wall serving for the application of ultra-violet radiations.

12. A device according to claim 7, in which the walls of the receptacle are of a substance different from the wall serving for the application of ultra-violet radiations.

13. A device according to claim 1, in which the walls of the receptacle other than the wall serving for the application of ultra-violet radiations are of a substance impermeable to the harmful ultra-violet radiations having a wave length less than that of the solar radiations.
